EDWARD BELL, JR., AND ISRAEL K. DIXON, OF JOHNSTOWN, PENNSYLVANIA

TONGUE SWITCH HOLDING DEVICE

Application filed November 24, 1931. Serial No. 577,068.

This invention relates to railway track structures and particularly to specific means and design of devices for holding down the heel of a tongue switch. The characteristic 5 feature of the design resides in the fact that a removable or replaceable pin is employed which need not resist lateral forces exerted on the switch. This pin is arranged to cooperate with the member which reacts upwardly on 10 the pin and downwardly on the switch heel so as to effectively normally hold the heel on its seat. And adjustable or compensating means are provided for exerting a force on the member so that wear on the heel can be compensated for. Further features of the invention reside in the specific arrangement of the parts 15 and the peculiar cooperative relationship more fully hereinafter described and claimed.

The invention will be apparent from the 20 following specification when read in connection with the accompanying drawings, in which:—

Fig. 1 is a plan view of a portion of the 25 switch structure embodying the invention with portions broken away and shown in section in the interest of clearness;

Fig. 2 is a vertical section on line 2—2 of Fig. 1;

Fig. 3 is a view similar to Fig. 1 illustrating 30 an alternative embodiment of the invention;

Fig. 4 is a section on line 4—4 of Fig. 3.

Referring in detail to the drawings, 10 35 represents the body portion of the switch which is provided with a bearing portion 12 including a substantially cylindrical bearing seat 14 for the heel portion 16 of the switch tongue 18. The bottom surface 20 of the heel is adapted to seat squarely on a bearing surface 22 of the switch body and the particular feature of the present invention relates to an improved design and arrangement of parts whereby the lower surface 20 of the heel is held down firmly in contact with the bearing surface 22 of the switch body. For 40 45 accomplishing this purpose, two alternative arrangements of the invention are shown.

In the design of Figs. 1 and 2, we provide 50 a pin 24 which is replaceable or removably secured in the switch body. This pin has a

flange 26 which bears on an overhanging shoulder 28 formed by counter-boring to the bottom of the switch body. The pin makes a relatively loose fit with the central hub portion 30 of the switch tongue and it is here 65 noted that the pin 24 is not intended to resist any transverse strains transmitted to the switch tongue or to the heel thereof, the chief function of the pin being to form a removable element of the hold-down device. The 60 pin has a hollow portion 32, as shown, and opening into this hollow portion, there is a slot 34, through which projects a member 36. The free end of this member reacts upwardly against the surface 38 of the pin and a portion 40 of said member engages a fulcrum portion 42 formed on the heel of the switch tongue. The tongue is transversely apertured, as indicated at 44, and the member 36 extends through this aperture and into a 70 chamber 46 formed in a box-like portion 48 of the switch body.

A bolt 50 passes freely through the outer extremity of the member 36 and the squared head 52 of this bolt is seated in a suitably 75 undercut slot 54, as shown. As thus arranged, it will be understood that by screwing down the nut 56, carried by the bolt, the member 36 can be rocked about the fulcrum 42 so as to cause it to react upwardly from 80 the surface 38 of the pin and downwardly on the fulcrum point 42 of the switch heel, thus tending to hold the switch heel firmly seated on the bearing surface 22 of the switch body. As wear occurs, it will be readily understood that the same can be compensated for by applying a suitable socket wrench or similar tool to the nut 56. Access, to this 85 adjusting nut, may be gained by removing a cover 58, which normally encloses the parts 90 within the chamber 46.

In the modified construction, shown in Figs. 3 and 4, the switch body 10^a includes a box-like portion 46^a, to which access may be gained to a wear take up device, indicated as a whole at 60. This device comprises a wedge member 62, the inclined surface 64 of which reacts against the upper surface 66 of a slot extending transversely through a pin 68, which serves substantially the same 100

function as the pin 24 referred to in the construction of Figs. 1 and 2. The lower surface 70, of the member 62, bears against a substantially flat bearing surface 72 forming part of the heel of the switch tongue 18.

The wedge member 62, at its outer end, is formed with a threaded shank 72, which carries an adjustable nut 74. Centered by the shank and bearing against the nut 74, there is a compression spring 76, which reacts against the upstanding lug 78 formed in the chamber 46 of the switch body. As thus arranged, it is clear that the spring 76 pressing against the nut 74 urges the wedge member 62 toward the pin and that the arrangement of the parts is such that the wedging action reacts upwardly on the pin 68 and downwardly on the surface 72 of the switch heel, thereby tending to hold the heel firmly on its seat. As wear develops, it will be appreciated that the spring will expand to automatically compensate for such wear. It will also be appreciated that by turning up the nut 74, adjustability of the wear take-up is provided for.

In both of the embodiments of the invention above described, it is to be noted that the holding down force is effected substantially at the center of oscillation of the switch heel and the holding down force is exerted against a removable pin member, whose chief function is to serve as a hold down device and that this pin is not subjected to any lateral strains, nor is it intended to serve in any sense as a pivot for the switch tongue. One feature of the design lies in its simplicity of construction, there being relatively few parts as compared with prior devices heretofore used. All parts can be readily removed for replacement or repair and various elements can be assembled, adjusted, or replaced with accuracy and dispatch.

While we have described quite specifically the specific design and arrangement of parts herein illustrated, it is to be understood that the description and illustration is to be interpreted in an illustrative rather than a limiting sense and that the claims are to be construed as broadly as is consistent with the prior state of the art.

What we claim is:

1. A tongue switch, comprising a switch body, a tongue having a heel portion journaled in a bearing of the switch body, said bearing including a seat, a hold-down device comprising an apertured pin mounted in a seat formed in the bottom of the switch body and a member entering the aperture in the pin and reacting upwardly on the apertured part of the pin and downwardly on the switch heel and means exerting a force on said member, tending to hold the heel of the switch firmly down on its seat.

2. A tongue switch, comprising a switch body, a tongue having a heel portion jour-

nalled in a bearing of the switch body, said bearing including a seat, a hold-down device comprising a pin having a flange which is removably seated against a shoulder formed in the switch body, a member extending laterally of said pin and reacting upwardly thereon and downwardly on the heel and means tending to move said member relatively to the pin and the switch body, so as to firmly hold the heel of the tongue down on said seat.

3. A tongue switch comprising a switch body, a tongue having a heel, a seat in the switch body for said heel, a pin removably seated in the switch body and extending axially into and pivotally engaging said heel, a member fulcrumed on said heel and reacting upwardly against said pin and means engaging the switch body and said member tending to rock the member on said fulcrum.

4. A tongue switch comprising a switch body, a switch tongue having a heel portion whose entire under side is flat and devoid of projections, said heel being journaled in the switch body, a switch body having a flat tongue seat, a pin removably secured in said switch body and extending upwardly through the tongue seat into said heel, a member fulcrumed on a portion of the heel and extending to the interior of said pin, a bolt reacting against the switch body and carrying a nut capable of rocking said member about said fulcrum.

5. A tongue switch comprising a switch body, a tongue having a heel portion journaled therein, a switch body having a seat for said heel, a hold-down pin removably seated in the switch body, said pin being slotted transversely and having a wedge face, a wedge member projecting through the slotted pin and means carried by the wedge member and reacting against the switch body, tending to force the wedge member transversely of the pin so as to press the heel firmly on said seat.

In witness whereof, we have hereunto signed our names.

EDWARD BELL, JR.
ISRAEL K. DIXON.
